UNITED STATES PATENT OFFICE.

MARTIN HURWITZ, OF JACKSONVILLE, ILLINOIS.

ATTACHMENT FOR TROUSERS.

1,076,581.

Specification of Letters Patent.

Patented Oct. 21, 1913.

Application filed December 3, 1910. Serial No. 595,426.

To all whom it may concern:

Be it known that I, MARTIN HURWITZ, a citizen of the United States, residing at Jacksonville, in the county of Morgan and State of Illinois, have invented new and useful Improvements in Attachments for Trouser, of which the following is a specification.

This invention relates to improvements in outer garments and more particularly to trousers.

The object of the invention is to provide a garment of this character which may be converted from a cuff bottom trouser to a straight trouser or vice versa, and which is provided with means for protecting the trouser bottom and cuff when in either position.

A still further object of the invention is the improvement of the structure shown in Farley, 923,345 of June 1, 1909. This construction has many disadvantages. When the trousers are worn with a cuff bottom, there is no protector to prevent wearing of the lower edge of the cuff and when the trousers are worn as straight bottom trousers there is no protection for the cuff which becomes so worn that it is unpresentable and cannot be turned up into cuff form. Then, there is no means provided by which the cuff may be secured in its interior position so that it will not be disarranged when the trousers are put on.

It is the object of this invention to avoid this difficulty and broadly speaking consists in the provision of a protector arranged within the trousers and adapted to overhang the cuff so as to secure the same in position and to protect it when the trousers are used with straight legs and also to protect the bottoms of the trousers when used with cuffs.

Further objects of the invention will appear as the following specific description is read in connection with the accompanying drawing which forms a part of this application, and in which:

Figure 1 is a perspective view of one leg of a pair of trousers provided with a cuff with parts broken away. Fig. 2 is a vertical section on an enlarged scale with the hem turned to form a cuff. Fig. 3 is a similar view showing the cuff concealed.

Referring more particularly to the drawing 1 represents one leg of a pair of trousers

which is provided with a cuff 2 adapted to 55 be worn on the outside or upon the inside of the leg as shown in Figs. 2 and 3. This cuff is provided by folding an extension of the material of which the leg is formed upwardly as at 3 along the side of the leg 60 and folding the remaining part of the extension as at 4 upwardly to connect with the folded portion 3 and the main portion of the trousers leg by blind stitching 5. This stitching being arranged intermediate 65 the width of the cuff 2 a half of the cuff extends above the lower edge of the trousers leg as indicated at 6 and the opposite half of the cuff extends below the point 6. Thus it will be seen that by folding the cuff inwardly, the inner side of the upper portion of the cuff forms a straight extension to the leg of a length equal to the length of the trousers when the cuff is folded up. So far as the structure has been described it 70 is substantially the same as the structure indicated in the Farley patent and has the disadvantage of bringing the cuff when turned inwardly into direct contact with the shoe of the wearer, thus allowing the same to 75 become disarranged or pushed out and soiled to such an extent as to render it unfit for use as an external cuff. In order to avoid this difficulty, a shield or protector 7 is stitched by blind stitching 8 or otherwise 80 secured to the inside of the leg of the trouser immediately above the upper edge of the cuff when in interior position and depends considerably below the point 6 so as to protect the cuff when turned inwardly 85 and also to secure and prevent the soiling of the bottom of the cuff when turned outwardly. The protector 7 may be made of the same material as the trousers or any other suitable material which is less costly 90 and has better wearing qualities as the protector is concealed at all times, and it is turned outwardly at its lower edge and stitched so as to provide a bead 7^a for engagement with the trouser cuff adjacent its 95 lower edge, when in either position, and which serves as means for making the lower edge of the shield more rigid, so as to more securely retain the cuff in its interior position. The protector also prevents the cuff 100 from being pushed out when the trousers are put on and thereby has quite an advantage over the structure shown in Farley 105

whose cuff is exposed and is in the way of the wearer's foot when putting on the trousers.

Having thus described the invention, what is claimed is—

- 5 1. A trousers leg having an integral cuff formed at its lower end and centrally connected to the same, said cuff adapted to be turned interiorly or exteriorly, and means secured to the inside of said leg whereby the cuff may be secured in its interior position so as to prevent disarrangement of the same, said means further serving to protect said cuff in either position.
- 10 15. 2. A trousers leg having an integral cuff formed at its lower end and centrally connected to the bottom of the same, said cuff adapted to be turned interiorly or exteriorly, and means for securing said cuff in its interior position to prevent disarrangement of the same comprising a shield of pliable material secured to the inner surface of the trouser leg above the lower edge of the same

and adapted to overlie the cuff when in its interior position, said shield extending to 25 a point adjacent the lower edge of the cuff in either position so as to protect the same.

3. A trousers leg having an integral cuff formed at its lower end and centrally connected to the bottom of the same, said cuff 30 adapted to be turned interiorly or exteriorly, and a retaining shield secured within the trouser leg above the lower edge of the same and adapted to overlie the cuff when in its interior position, said shield extending to 35 a point adjacent the lower edge of the cuff and provided with a folded bead on the outer face of its lower edge for engagement with the inner face of the cuff.

In testimony whereof I affix my signature in presence of two witnesses.

MARTIN HURWITZ.
